UNITED STATES PATENT OFFICE.

HARRY A. HOUSEMAN, OF PHILADELPHIA, PENNSYLVANIA, ASSIGNOR TO STANDARD MACHINE COMPANY, OF PHILADELPHIA, PENNSYLVANIA, A CORPORATION OF PENNSYLVANIA.

CIRCULAR-KNITTING MACHINE.

1,078,677.

Specification of Letters Patent. Patented Nov. 18, 1913.

Application filed May 17, 1912. Serial No. 697,861.

To all whom it may concern:

Be it known that I, HARRY A. HOUSEMAN, a citizen of the United States, residing at Philadelphia, county of Philadelphia, and State of Pennsylvania, have invented a new and useful Improvement in Circular-Knitting Machines, of which the following is a full, clear, and exact description, reference being had to the accompanying drawings, which form a part of this specification.

The object of my invention is to construct a circular knitting machine, adapted especially to the manufacture of ladies' and children's stockings and men's half hose. The invention comprises a number of novel features, including improvements in the driving mechanism, in the mechanism for shifting from rotation to reciprocation and vice versa, in the mechanism for moving the needles into and out of action, in the means dictating the introduction and removal of an extra thread, in the mechanism for lifting the needle cylinder simultaneously with the introduction of an extra thread; in the means for controlling the fashioning in the leg and the knitting of a garter top at the upper portion of the leg, in the means for automatically stopping the machine in the manufacture of half hose and also in the event of any obstruction to rotation of the cam cylinder, in the means for manually leveling the needle cylinder, in the special means for rendering certain needles inactive in the manufacture of half hose preparatory to leveling the needles for transferring, and in various other features and structural details.

In the drawings: Figure 1 is a front elevation of the machine; Fig. 2 is a sectional plan on the line 2—2 of Fig. 1; Fig. 3 is a side view looking toward the left side of Fig. 1; Fig. 4 is a detail side view of the mechanism controlling the means for lifting the needle cylinder to its maximum height. Fig. 5 is a detail side view of one of the main pattern ratchets and part of the mechanism for shifting from rotation to oscillation and vice versa. Fig. 6 is a section on the line 6—6 of Fig. 2; Fig. 7 is a partial side view looking toward the right of Fig. 1; Fig. 8 is a section on the line 8—8 of Fig. 1 showing the belt-shifting mechanism. Fig. 9 is an enlarged vertical section of the driving mechanism for the cam cylinder and sinker head; Fig. 10 is a partial section on

the line 10—10 of Fig. 9; Fig. 11 is a plan view of the means for vertically moving and leveling the needle cylinder. Fig. 12 is a partial rear elevation. Fig. 13 is a detail view of a part of the top motion control mechanism. Fig. 14 is a detail plan view showing the means for rendering inactive one of the main pattern ratchets. Fig. 15 is a section on the line 15—15 of Fig. 14.

a is the frame of the machine and *b* the upper bed plate. Projecting upward from the bed plate *b* is a spider *c* on which rests the non-rotatable needle cylinder *d*. The needle cylinder *d* has slots *e* extending from the inner periphery outward. These slots 79 contain the needles *f* which are operated from needle levers *g* pivoted on the comb *h*. The comb *h* rests on the bed plate *b*. The rotatable cam cylinder *i* is located within the needle cylinder *d*. The above described 75 construction is the same as that shown in Patent No. 903,190 issued to me November 10, 1908.

Resting on the needle cylinder *d* is the sinker head *k* having the cap *l* having cams 89 adapted to actuate the sinkers or web holders *z*.

As is well understood, during the knitting of the leg of the stocking and during the knitting of that part of the stocking between the heel and toe (which I shall call the foot) the cam cylinder is continuously rotating and all the needles are in action and in the position shown in Fig. 9. During the knitting of the heel and toe, the cam cylinder 90 is oscillated and the needles extending throughout one-half the circumference of the needle bed (hereinafter referred to as the rear bank of needles) are initially thrown out of action, which is effected by 95 moving down a half-ring *m* engaging the tails of the needle levers corresponding to said needles, whereby said needles are swung outward and out of operative engagement with the knitting cams. During the oscillation of the cam cylinder, the needles extending throughout the remaining semi-circumference of the needle bed (that is, the front bank of needles) are thrown out of action one at a time, first at one end of the semi-circumference and then at the other end, and so on alternately until a limited number of needles in the central part of the semi-circumference are in action; the needles are then thrown into action one at a time in 110

approximately the reverse order in which they are thrown out. This operation is effected, in a manner known in the art, by means of two fashioning rock-plates *o* actuated by two double pawls *p* carried by two arms *s* projecting from an oscillating ring *r*.

The shift of the cam cylinder *i* from rotation to reciprocation, the depression of the half-ring *m* for throwing half the needles out of operative connection with the knitting cams, and the imparting of oscillating motion to the ring *r*, for throwing certain of the remaining needles, one at a time, into and out of operative connection with the knitting cams, are effected at the same time by means to be hereinafter described.

It will be understood that the cam cylinder *i* and sinker cap *j* are rotated and oscillated together. The cam cylinder at its lower part has on its outer face a gear 11 engaging the outer gear 13 of a ring 12. The ring 12 carries also an inner gear 14 which engage a pinion 15 on the shaft 16. The shaft 16 also carries a pinion 17 which engages a gear 18 on the sinker head *k*. The ring 12 is the driving element of the chain of gearing described. As shown, the ratio between gears 11 and 13 is one to one, between pinion 15 and gear 14 one to two, and between gear 17 and gear 18 one to two, and the cam cylinder and sinker head therefore have imparted to them precisely similar movements, as if they were rigidly secured together.

The ring 12, from which both the cam cylinder *i* and sinker cap *j* derive their movements as above described, is driven from the clutch-shaft 20 by means to be hereinafter described. On the clutch shaft 20 are slidably mounted the two pinions 21 and 22, which have sleeves to which are yoked the vertically movable arms 24, 24, which are moved up or down in unison as hereinafter described. The clutch 23 is fixed on the shaft 20, between pinions 21 and 22. The upper pinion 21 is constantly rotated and the lower pinion 22 constantly oscillated. When the arms 24 are moved down, thus engaging the rotary pinion 21 with the clutch 23 and disengaging the oscillatory pinion 22, the ring 12 is continuously rotated, thus rotating the cam cylinder *i* and sinker cap *j*. When the arms 24 are elevated, thus disengaging the rotary pinion 21 from the clutch 23 and engaging the oscillatory pinion 22, the ring 12 is constantly oscillated, thus oscillating the cam cylinder *i* and sinker cap *j*.

The pinion 21 is constantly rotated by means of a spur gear 25 meshing with the pinion 21. The shaft 26 of the spur gear 25 also carries a bevel gear 27 driven from a bevel pinion 28 on the driving shaft *t*.

The pinion 22 is constantly oscillated by the following means. On the shaft 26 is

a crank 29 connected by a link 30 with an arm 31 turning on a shaft 32. Extending from the hub of the arm 31 is a quadrant 33 engaging the pinion 22.

The ring 12 is of substantially greater thickness than the gears 13 and 14 carried by it. The part of the ring 12 projecting below the gears 13 and 14 rotates in a cup-shaped casing 35 through which the upper end of the clutch shaft 20 projects. The clutch shaft 20 has secured to it spider 36. A latch 37 extends from the axis of the shaft 20 through one arm of the spider 36 into a beveled recess in the inner face of the ring 12. The outer end of the latch 37 is correspondingly beveled and is held in the recess by means of a spring 38. The inner end of the latch is beveled and engages the beveled upper end of a rod 39 extending axially through the clutch shaft 20. It will thus be seen that the drive between the clutch shaft 20 and the ring 12 is not a positive one. So long, however, as there is no obstruction in the knitting mechanism tending to stop the operation of the cam cylinder *i* or sinker cap *j*, these members are driven from the clutch shaft 20 as if the ring 12 were positively secured thereto; but in the event of any obstruction to the operation of the cam cylinder *i* or sinker cap *j*, the latch 37 will be forced inward, thus destroying the driving connection between the shaft 20 and the ring 12. At the same time the rod 39 will be depressed, and the machine stopped by means which I shall now describe (see Figs. 1 and 8).

On the driving shaft *t* are the fixed driving pulley 40 and the loose idle pulley 41. 42 is a belt-shifter secured to the slideable shaft 43. A spring 44 tends to move the shaft 43 into position to cause the belt shifter 42 to move the belt into engagement with the loose pulley 41. By means of a hand lever 45 engaging a collar 46 on the shaft 43, the shaft 43 and belt-shifter 42 may be moved into position to bring the belt into engagement with the driving pulley 40, the shaft 43 being retained in this position by means of a latch 48 (on the collar 46) dropping back of a lug 49 on a bell-crank lever 50. The lower end of the rod 39 rests upon one end of an intermediately pivoted lever 51, the other end of the lever 51 extending under and between the ends of, a lever 52. The lever 52 is pivoted at one end and its other end is hooked over one end of a lever 53, the other end of lever 53 engaging one arm of the bell-crank lever 50.

When the rod 39 is depressed, as above described, it rocks the lever 51, and the lever 51 in turn rocks the lever 52, the hooked end of the latter thereby being withdrawn from engagement with the lever 53. The latter is thus released, and under the influence

on a spring 54, moves the bell-crank lever 50 into position to cause the lug 49 to recede from the latch 48, whereupon the spring 44 moves the belt-shifter 42 into position to shift the belt from the driving pulley 40 to the loose pulley 41, thereby stopping the machine.

The mechanism for vertically moving the arms 24, and thereby changing from rotation to oscillation, and vice versa, will now be described. These arms are secured to a post 60 (see Figs. 2, 5 and 6). The post 60 has a pair of collars 61 between which extend the forked ends of a lever 62 pivoted between its ends on the frame of the machine. The lever is actuated by means of a double cam 63, 64 secured to a sleeve 67 on the shaft 69 (see Figs. 5 and 12). These cams rotate together and may be integral 15 one with another. Each cam has a high part and a low part. The high part of cam 63 is adapted to coact with an arm 65 on the lever 62. The high part of cam 64 is adapted to coact with an arm 66 on the lever 62. 20 When the high part of cam 63 coacts with the arm 65, the post-engaging end of the lever 62 is moved and held down, thereby moving down the post 60, the arms 24 and the pinions 21 and 22, thereby clutching pinion 21 with the clutch 23 and dictating the rotation of the cam cylinder *i* and sinker cap *j*. When the high part of cam 64 coacts with the arm 66, the post engaging end of the lever 62 is moved and held up, 25 thereby dictating the oscillation of the cam cylinder *i* and sinker cap *j*. The length of the high part of each cam 63 and 64 corresponds with the length of the low part of the other cam, and the arrangement is such 30 that when the high part of one cam starts to ride under its corresponding lever arm, the high part of the other cam starts to recede from its corresponding lever arm. Thus the lever 62 is always in positive engagement with one cam or the other. The 35 double cam 63, 64, is caused to turn by means of a pattern ratchet wheel 68, also secured to the sleeve 67, which ratchet wheel is turned initially by first turning the 40 sleeve 67 and then by means of a pawl 70. The following means are provided for initially turning the sleeve 67: *u* is the pattern chain, the same extending around sprocket wheels 71 and 72, the former being 45 driven by means to be hereinafter described. Just before it is desired to change from rotation to oscillation, one of the lugs *v* on the pattern chain engages a cam lever 73, pivoted on the machine frame, and rocks the 50 same. The cam lever 73 is connected, by means of a link 74, with a lever 75 pivoted on the cam shaft 77. The lever 75 carries a pawl 76 adapted when actuated from the cam lever 73 through the medium of link 55 74 and lever 75, to engage a single-toothed ratchet 770 on the cam shaft 77 and thereby turn the same. The cam shaft 77 is geared to the sleeve 67 by means of the intermeshing pinions 78 and 79, and thereby the sleeve 67, together with the double cam 70 63, 64 and the ratchet wheel 68, are turned. The pawl 70 is constantly reciprocated, by means to be hereinafter described. By reference to Fig. 5 it will be noticed that the ratchet wheel 68 has a number of teeth 75 (seven are shown) of which one, 80, is substantially longer than the others. During oscillation of the cam cylinder, the pawl 70 plays upon the long tooth, its extent of movement being insufficient to cause it to drop back of the same. Consequently, it is inoperative to turn the ratchet wheel 68. But after the ratchet wheel 68 has been turned by the pattern chain, through the mechanism just described, the long tooth is 80 advanced to such position that on the next reciprocation of the pawl 70 it drops back of the long tooth 80 and proceeds to turn the ratchet-wheel, together with the double cam 63, 64. In the embodiment of 85 my invention shown, as the pawl 70 actuates the first tooth of the ratchet 68, the cam 190 on the cam shaft 77 actuates a bell-crank lever 191 (see Figs. 12 and 13) which lifts a rod 149. This rod, which is normally 90 held down by a spring 192, controls the actuation of the top-motion for introducing a supplemental or reinforcing thread to the needles. This top-motion is not herein shown, as it forms no part of the present invention, but the same may be understood by reference to the patent issued to me August 9, 1910, No. 937,019, in which the rod 18 corresponds to the above mentioned rod 149. As the pawl 70 engages and pushes 95 the second tooth of the ratchet 68, the high part of cam 63 recedes from the lever arm 65 and the high part of cam 64 engages lever arm 66, thereby lifting the post-engaging end of lever 62, clutching the lower or oscillatory pinion 22 to the clutch shaft 20 and unclutching the rotary pinion 21, and causing the cam cylinder *i* and sinker cap *j* to oscillate. The constant reciprocation of 100 the pawl 70 is effected by securing to the hub of lever 31 a section of a bevel pinion 81 which drives a similar pinion 82 on the shaft 69. To this shaft is secured a holder 83 carrying the pawl 70. 105 On the shaft 69 is a crank pin 85 connected, by means of a link 86, with a lever 87 pivoted on the shaft 88 of the sprocket wheel 71. This lever 87 carries a pawl 89 which engages a ratchet wheel 90 on the shaft 88. As before described, the shaft 69 110 is constantly oscillated from the lever 31 by means of pinions 81 and 82; and by means of the link 86, lever 87 and pawl 89, the ratchet wheel 90 is turned and the sprocket 115 chain advanced.

At the same time that the machine is shifted from rotation to oscillation, it becomes necessary, as hereinbefore described, to throw out of action the rear bank of needles, which, as stated, is effected by moving down the half-ring *m* engaging the tails of the needle levers *g* corresponding to said needles, whereby said needles are swung outward and out of operative engagement with the knitting cams. The half-ring *m* is secured to a cross-bar 92 carried by an upright rod 93. The rod 93 is carried by one end of a lever 94, which is bifurcated between its ends and pivoted, at its bifurcated portion, on the machine frame. The other forked end of lever 94 embraces a stud 95, being confined between a head fixed on the top of the stud and a sleeve 97 loose on the stud, said sleeve forming the end of an arm on the lower end of the post 60. On the lower end of the stud 95 is a head 98, between which and the sleeve 97 is confined a coil spring 99.

When the post 60 is raised, as it is in shifting from rotation to oscillation, the sleeve 97 is raised with it, thereby lifting the forked end of lever 94 and lowering the other end of the lever, thereby pulling down the rod 93, bar 92 and half-ring *m* and rendering inoperative the rear bank of needles. When the post 60 is lowered, as it is in shifting from oscillation to rotation, the sleeve 97, acting against spring 99, pushes down the stud 95 and the forked end of lever 94, thereby elevating the half-ring and rendering the rear bank of needles again operative.

As soon as the machine is shifted from rotation to oscillation and the rear bank of needles is thrown out of action, it becomes necessary to oscillate the ring *r* which, as before described, actuated the fashioning rock-plates *o* through the medium of the arms *s* and the double pawls *p*. The oscillation of the ring *r* is effected by the following means. On the ring *r* is an arm 100 from which depends a stud 101. Slidable on the stud 101 is a sleeve carrying a cam roller 103. Attached to the sleeve is one end of a lever 104 pivoted between its ends on a horizontal axis. The other end of lever 104 has forks embracing a projection from the upper arm 24 which, as before stated, is yoked around the sleeved portion of the rotary pinion 21.

The upper face of the gear wheel 25 is recessed to form an annular cam-way having an outside cam 106 and an inside cam 107. When the arms 24 are depressed to lower the pinions 21 and 22 and cause the cam cylinder and sinker cap *j* to continuously rotate, the cam roller 103 will be raised so as to lift it out of the line of travel of the cams 106 and 107; but when the arms 24 are raised to raise the pinions 21 and 22 and cause the cam cylinder and sinker cap *j*

to oscillate, the cam roller is depressed and moved into line of travel of the cams 106 and 107. Thereafter, during reciprocation, the cam roller is actuated, first by one cam and then by the other, causing the ring *r* to oscillate, thereby actuating the fashioning rack-plates *o*.

I have now described the means for changing from rotation to oscillation and for simultaneously rendering operative the means for shifting the rear bank of needles out of action and for starting the operation of the fashioning rack plates. As before stated, this occurs at the beginning of the knitting of the heel and at the beginning of the knitting of the toe. During the knitting of the heel and toe it is desirable to decrease the tension on the thread so as to permit of the insertion of an extra reinforcing thread, as hereinbefore described. When said extra thread is introduced and said shift from rotation to reciprocation occurs, certain mechanism, which I will now proceed to describe, operates to lift the needle cylinder and the sinker head resting thereon; thereby, as is well understood in the art, decreasing the tension on the thread.

Threaded in the spider *c* are screws 110 (see Figs. 9 and 11) carrying pinions 111 meshing with an internal rack or gear 112, resting on the spider *c*. Supported on the axles of the pinions 111 are parts 113 secured to the needle cylinder. By imparting a rotary movement to the gear 112, the screws 110 are rotated, thereby moving the needle cylinder vertically. By this means a very fine and certain adjustment of the vertical position of the needle cylinder is secured. Further, by lifting gear 112 out of engagement with the screws, any one of them can be independently turned a distance of one or more pinion teeth. This is of special advantage in case the needle cylinder should not be absolutely level, as it can be leveled perfectly by independently adjusting one or more of the screws.

The gear 112 is turned at the proper time automatically by means of the following mechanism (see also Figs. 3 and 11). Secured to the gear 112 is a bracket 114 to which is pivoted a rod 115 slidable in a bearing in the standard 120, on the upper bed plate *b*. Secured to the rod 115 are two adjustable pieces 116, 117 carrying respectively screws 118, 119, whose axes are parallel to the axis of the rod 115. The upper end of one arm of a three-armed lever 121 extends back of the screw 118. Another arm of the lever 121 is in line of travel of a cam 122 on the shaft 77. As before described the cam shaft 77 is given a preliminary turn in order to give a preliminary turn to the ratchet wheel 68 to bring it into operative relation with the pawl 70. During the time that the ratchet wheel 68 and cam 122

shaft 77 are being turned to shift from rotation to oscillation as before described, the cam 122 underrides the lever 121 and causes it to engage and push the screw 118 and rod 115, thereby turning the gear 112 and lifting the needle cylinder.

The extent to which the needle cylinder will lift may be governed by adjusting the piece 116 on the rod 115, or more conveniently and accurately, by turning the screw 118.

The extent to which the needle cylinder may be depressed is governed by a screw 220 against which an abutment 221, secured to the gear 112, is adapted to strike on the return movement of the gear 112. The screw 220 is adjustable in a bracket 222 secured to the spider *e*. A spring pressed detent 223 engages the grooved head of the screw and holds the screw in its adjusted position.

So long as the pawl 70 is in operative relation with the ratchet wheel 68, the ratchet wheel will turn a distance of one tooth at each four rotations of the driving shaft. As continued rotation of the ratchet wheel 68 will dictate the shifting from oscillation to rotation, I have provided mechanism to hold the ratchet wheel stationary until the heel or toe is completed and it is desired to return to circular knitting. This mechanism (see Figs. 6, 14 and 15) is arranged to withdraw the pawl 70 from action when it has turned the ratchet wheel 68 two more teeth. I have explained that the fashioning rack plates *o* start to reciprocate as soon as the shift from rotation to oscillation is completed. One of these rack plates carries a cam 125 which, when the rack plates are in the position they occupy during rotation, extends under, and holds up, the outer end of an arm 126 on a rock shaft 127. The rock shaft 127 has an arm 128, which is connected, by means of a link 129, with a dog or guard 130, located adjacent to the pawl 70. When the cam 125 engages the arm 126 as described, the pawl is free to drop into engagement with the ratchet wheel 68, but immediately after the plates *o* start to rack, the cam 125 recedes from the arm 126, allowing it to drop, thereby rocking the shaft 127 and moving the dog 130 so as to tilt the pawl 70 out of engagement with the ratchet wheel 68.

The pawl 70 remains in its inoperative position throughout the knitting of the heel and of the toe. When the knitting of the heel or toe is completed, the plates *o* have racked back into their original position and the cam 125 passes under the arm 126, thereby, through shaft 127, arm 128 and link 129, lifting the dog 130, and allowing the pawl 70 to drop into operative position. The pawl immediately turns the ratchet wheel 68 another tooth, thereby effecting simultaneously the following operations: In the first

place, the high point of cam 63 rides under the arm 65 of lever 62 and at the same time the high point of cam 64 recedes from the arm 66 of lever 62, thereby moving down the post 60, arms 24 and pinions 21 and 22, and clutching the rotary pinion 21 with the clutch shaft 20, causing the cam cylinder *i* and sinker cap *j* to rotate. In the next place, the depression of post 60 rocks the lever 94, causing it to raise the rod 93, bar 92 and half-ring *m*, thus again rendering operative the rear bank of needles. In the next place, the depression of the upper arm 24 carried by the post 60 rocks the lever 104 and lifts the cam-roller 103 out of line of travel of the cams 106 and 107, thereby stopping the oscillation of the ring *r* and the actuation of the rack plates. In the next place, the cam 122 rides from under the lever 121, thereby allowing the rod 115 to be returned to its original position by means of the spring 123, thereby turning the gear 112 and screws 110 to lower the needle cylinder.

The above described series of operations occurs after the knitting of both the heel and toe, with the exception that, after the knitting of the toe, it is desired to retain the needle cylinder lifted and also, usually, to lift it still higher, preparatory to the knitting of the upper portion of the leg. This part of the leg, in ladies' hose, is knit with a reinforced thread to form a "garter top," and I have provided the following means to prevent the needle cylinder from dropping after the cam 122 travels beyond the lever 121 and to raise it still higher so as to still further slacken the loops.

On the shaft 77 is a cam 132 (see Fig. 4) having two high points coacting with a roller 133 on a lever 134 pivoted at its lower end. 136 is a lever, pivoted between its ends adjacent to the shaft 88 of the sprocket wheel 71, and connected by means of a link 135 with the lever 134. Loose on the shaft 88, and secured together, are a ratchet wheel 137 having three teeth and a cam wheel 138. 139 is a pawl, hung from the pivot between link 135 and lever 136 and playing on the ratchet wheel 137. In passing from the heel to the foot, the ratchet wheel is in such position that the pawl 139, when operated, plays idly on the untoothed periphery of the ratchet wheel 137; but during the knitting of the toe, one of the pins 140 projecting from the pattern chain engages one of the lugs 141 on the ratchet wheel 137 and turns the latter to such position that the first tooth of the ratchet wheel 137 is in operative relation with the pawl 139. The cam 132 is so arranged that the first high point thereon engages the lever 134 during the ratcheting of the fifth tooth of ratchet wheel 68—that is, the one which, when ratcheted, effects the change from oscillation to rotation. The actuation of lever 134 at this time—that is, 130

in passing from the toe to the leg—causes the pawl 139 to engage the first tooth of the ratchet wheel 137 and turn it a distance of one tooth. This causes the cam face of cam wheel 138 to ride under one arm of a two armed lever 142 pivoted on the machine frame. The other arm of this lever 142 is thereby caused to engage the screw 119. This engagement occurs at the same time that the lever 121 is receding from the screw 118, thereby preventing the rod from being returned to its original position and holding the needle cylinder in its raised position. It will, of course, be understood, that whether the needle cylinder is retained, by the action of lever 142, at exactly the same level to which it was raised by the lever 121, or whether it is allowed to drop slightly, or whether it is raised to a slightly greater height, depends upon the adjustments of the two screws 118 and 119.

During the ratcheting of the next or sixth tooth of the ratchet wheel 68 (which occurs after four more turns of the main driving shaft), the second high point of the cam 132 engages the lever 134 and causes the pawl 139 to actuate the second tooth of the ratchet wheel 137 and thereby turn the cam wheel 138 into such position that the adjustable cam piece 143 thereon rides under the lever 142 and causes it to advance the rod 115 still further, thereby still further turning the gear 112 and screws 110 and still further lifting the needle cylinder, thus still further increasing the slackness of the loops. The cam wheel 138 and ratchet wheel 137 remain in this position during the knitting of the garter top. When the desired length of garter top has been knitted and it is desired to pass from the garter top to plain single-thread circular knitting, a lug 144 on the pattern chain engages a cam 145 on the lever 136, thus again actuating the pawl 139 and causing it to ratchet the third tooth of the ratchet wheel 137. This causes the cam piece 143 to ride from under the lever 142, which recedes a certain distance from the screw 119 and permits the spring 123 to draw back the rod 115 and lower the needle cylinder. It is not desired, however, to immediately lower the needle cylinder to its normal level; that is, to the level which it occupies during the knitting of the ankle and foot: for the reason that it is desired to continue to knit a certain length of leg below the garter top of maximum width. It is therefore desired, notwithstanding that the reinforcing thread is clamped and cut as soon as the garter top is completed, to maintain a certain degree of slackness in the loops of the yarn. Consequently, the periphery of the cam wheel 138 is so formed that the part beyond the cam piece 143 is still high relatively to the low part of the periphery, and therefore the needle cylinder,

as above described, is not lowered to its lowest level. It may be mentioned here that, when the ratchet wheel 137 and cam wheel 138 are given their final turn by the pawl 139, one of the lugs 146 on the cam wheel 138 engages one arm of a two armed lever 147, causing the other arm of this lever to move from under a projection 148 of the rod 149, allowing the latter to move down. The moving down of rod 149 permits the thread to be clamped and cut.

The ratchet wheel 137 and cam wheel 138 remain stationary during the knitting of that part of the leg below the garter top and above the ankle. In passing to the ankle part of the leg, it is desired to fashion the fabric; that is, to gradually decrease its diameter. This is effected by gradually increasing the tension on the yarn, which in turn is effected by gradually lowering the needle cylinder to its lowest level. At the point where it is desired to so gradually lower the needle cylinder, another of the pins 140 projecting from the pattern chain engages another of the lugs 141 on the ratchet wheel 137 and turns the ratchet wheel 137 and cam wheel 138 a part of a revolution—say, something less than half a revolution. This causes the lever 142 to pass along that part of the periphery of the cam wheel 138 beyond the cam piece 143, which, it will be noticed, is a gradual incline descending to the low part of the periphery. During this operation, the lever 142 gradually recedes from the screw 119, and the spring 123 draws back the rod 115 until the gear 112 and screws 110 are turned to lower the needle cylinder to its lowest level. The machine now proceeds to knit the ankle, or lower portion of the leg. At this point it may be stated that after the second high point of the cam 132 engages the lever 134 and dictates the elevation of the needle cylinder to its maximum height, the pawl 70 returns the ratchet wheel 68 to the position where the pawl 70 plays idly on the long tooth 80, which continues until a lug on the pattern chain again actuates the lever 73 and thereby gives the ratchet wheel 68 its initial turn preparatory to again shifting from rotation to oscillation, which, as before described, occurs when the knitting of the ankle is completed and it is desired to knit the heel.

From the foregoing description it will be understood that the various operations hereinbefore described are all controlled by the turning of ratchet wheels 68 and 137 and it may be well, therefore, to briefly review the relative positions of these wheels during the entire cycle of operations.

Assume that the ankle, or lower portion of the leg, is being knit. During this operation, both ratchets 68 and 137 are stationary, the pawl 70 is playing idly on the long

tooth of ratchet 68, and the pawl 139 engages the untoothed periphery of ratchet 137. One of the lugs 146 on the cam wheel 138 is in engagement with lever 147 and the 5 rod 149 has been moved down. The cam cylinder and sinker cap are being rotated, the needle cylinder is at its lowest level, all the needles are active, and a single thread is passing to the needles. In passing from 10 the leg to the heel, ratchet 68 is turned, causing the cam 190 to lift the rod 149 and dictate the introduction of a reinforcing thread. Further turning of the ratchet wheel 68 dictates the first shift from rotation to oscillation, the moving out of action 15 of the rear bank of needles and the moving into operation the fashioning rack plates, which, after starting to operate, effect the withdrawal of the pawl 70 from ratchet 68 thereby stopping the latter from turning 20 further. At the same time that the shift from rotation to oscillation is effected, the needle cylinder is raised. This condition continues during the knitting of the heel, the ratchet 137 remaining stationary.

25 At the end of the heel knitting, the fashioning rack plates effect the reinstatement of the pawl 70 into operative position, and the ratchet 68 again starts to turn. This immediately dictates a shift from oscillation to rotation, the movement of the rear bank of needles into action and the rendering inactive of the fashioning rack plates. The cam 190 moves out of operative relation with the rod 149, allowing the latter to drop, thereby dictating the clamping and cutting of the reinforcing thread. The 30 needle cylinder is again lowered. The ratchet 68 continues to turn until the long tooth thereof is brought under the pawl 70, when its turning movement ceases. This condition continues during the knitting of the foot, the ratchet 137 remaining stationary.

35 In passing from the foot to the toe, ratchet 68 starts on its second complete rotation, causing the cam 190 to again elevate rod 149 and dictate the re-introduction of the reinforcing thread. Further turning 40 of the ratchet wheel 68 dictates the second shift from rotation to oscillation, the moving out of action of the rear bank of needles, the moving into operation of the fashioning rack plates, the latter dictating the withdrawal of the pawl 70 from ratchet 68, thereby stopping the latter from further 45 turning. At the same time that the shift from rotation to oscillation is effected, the needle cylinder is again raised. During the knitting 50 of the toe, one of the lugs 140 on the pattern chain turns the ratchet 137, causing the lug 146 that has engaged lever 147 to pass out of engagement therewith and allowing the long arm thereof to drop and the short 55 arm to move under the lug 148 and lock the

rod 149 from dropping. The ratchet 137 continues to turn (say slightly less than half a revolution) until, sometime before the toe 60 is completed, the pawl 139 drops back of the first tooth.

65 After the toe is knitted, the fashioning rack plates reinstate the pawl 70 into operative position, and the ratchet 68 again starts to turn. This immediately dictates another shift from oscillation to rotation and the 70 movement of the rear bank of needles into operative position, and the fashioning rack plates are again rendered inactive. At the same time the pawl 139 ratchets the wheel 137 a distance of two teeth, and the cam 190 75 again moves out of operative relation with the rod 149, which does not, however, drop, being upheld by the lever 147. The reinforcing thread therefore continues to feed to the needles. As the second tooth of the 80 wheel 137 is ratcheted, the highest point of cam 138 effects the lifting of the needle cylinder to its maximum height. The ratchet 68 continues to turn until the long tooth thereof is brought under the pawl 70, whereupon its rotation ceases. This condition 85 continues during the knitting of the "garter top" at the upper portion of the leg.

90 In passing from the garter top to the plain portion of the leg, the pattern chain 95 directly actuates the lever carrying the pawl 139 and the ratchet 137 is turned a distance of one tooth. This causes the highest point of cam 138 to recede from lever 142, whereby the needle cylinder is allowed to drop, 100 but not to its lowest level. At the same time, the second lug 146 engages the lever 147, whereby the rod 149 is released and allowed to drop to effect the clamping and severance 105 of the reinforcing thread. Both ratchets 68 and 137 now remain stationary until the fashioning of the leg begins. At this point the second pin 140 on the pattern chain again turns the ratchet 137 (say slightly less than half a revolution) causing the lever 142 110 to travel down the incline of cam 138, whereby the needle cylinder is allowed to drop to its lowest level. As soon as the ratchet starts to turn, the second lug 146 passes out 115 of engagement with the lever 147 the longer arm of which thereupon drops but its shorter arm does not engage the lug 148 of rod 149, the latter being in its lower position. As this turn of the ratchet 137 is completed, thus completing the fashioning, 120 the first lug 146 reengages the lever 147 but of course without causing it to perform any function. Thereafter, during the knitting 125 of the ankle, or lower portion of the leg, both ratchets 68 and 137 remain stationary (the ratchet 68 having remained so during the knitting of the garter top, the plain unfashioned portion of the leg below the garter top, and the fashioned part of the leg).

130 It will be observed that both ratchets are

now in the positions that they occupied at the beginning of the cycle of operations, and that a complete stocking has been knit entirely automatically. So long as the machine continues to operate and so long as 5 yarn is fed by the top motion, the cycle of operations is repeated and complete stockings continue to be knit.

While I have thus described the cycle of 10 operation as carried out in a machine in which the parts are arranged and adjusted as shown and described, it is obvious that such particular arrangement and adjustment is not obligatory, and that the same may be 15 varied in order to vary the particular cycle of operations described. For example, the particular cycle of operations described would not be followed in the knitting of half hose.

20 In order to adapt the machine to knit half hose, I have provided certain additional mechanism, which should be thrown out of action when it is desired to knit ladies' hose. In knitting half-hose, after the toe is completed, a number of round-and-round courses are knit. The machine is then stopped, preparatory to certain operations, well known in the art, to which I shall refer hereinafter. I will first describe the means for automatically stopping the machine.

I have already described how the actuation of the bell-crank lever 50 allows the spring 44 to actuate the belt shifter 42 to stop the machine. In automatically stopping the machine during the knitting of 35 men's hose, the actuation of the lever 50 is effected by means of a lever 160 (see Fig. 8) which is in turn actuated by a cam-wheel 161. This cam-wheel is on a shaft 162, which also carries the ratchet wheel 163. On the main driving shaft t is a spur gear 166, meshing with a spur gear 167 (see Fig. 7). A link 168 connects a crank pin on gear 167 with the outer end of the arm 165 at 40 which point is carried a pawl 170. The arm 165 is loosely pivoted on shaft 162. The pawl 170 engages the teeth of the ratchet wheel 163. These teeth extend all the way around the periphery of the wheel 163 except for a blank space somewhat shorter in 45 length than the space occupied by three teeth. Mechanism is provided (as herein-after described) whereby after the knitting of the toe is completed, the ratchet wheel 55 163 is turned to bring the first tooth of the wheel into operative relation with the pawl. Thereafter the ratchet wheel 163 will be turned a distance of one tooth at each revolution of the driving shaft. After the 60 ratchet wheel 163 is turned any predetermined number of teeth, the cam wheel 161 actuates the lever 160, which in turn rocks the lever 50, thereby permitting the spring 44 to move the belt-shifter 42 to shift the belt 65 from the driving pulley to the loose pulley.

If there are any additional teeth on the ratchet wheel 163, the latter, after the machine is re-started, continues to turn until the pawl 170 has actuated the last tooth, when it proceeds to play idly on the untoothed portion of the periphery of the 70 wheel.

The ratchet wheel 163 is subsequently turned to bring the pawl 170 again into operative relation with the ratchet wheel by 75 the following means. On the shaft 77 is a cam wheel 171. A bell-crank lever 172 is pivoted on the machine frame, one arm of the lever being held in contact with the cam face of the wheel 171 by a spring 173 80 and the other arm of the lever being connected to the upper end of a link 174, the lower end of this link having a pin and slot connection with the intermediate part of a lever 175. This lever is pivoted at one end 85 on the machine frame and at the other end has a projection in line of travel of a lug 176 on the ratchet wheel 163. On the link 174 is a fixed pawl 177 adapted to engage the ratchet wheel 163. A spring 178, extending between projections on the lever 175 and link 174, maintains the pawl 177 in engagement with the teeth of the wheel 163.

Just before the first shift from oscillation to rotation (which occurs in passing from 90 the heel to the foot) the cam wheel 171 (which is provided with two high points, the second being higher than the first) engages the lever 172. As the lever 172 rides upon the first high point of the cam wheel 100 171, the link 174 is depressed, thereby disengaging the projection on the end of lever 175 from the lug 176 and unlocking the ratchet wheel 163. The link 174 is not, however, on this movement, depressed sufficiently 105 to cause the ratchet wheel to be turned. In shifting from oscillation to rotation, however, the cam wheel 171 is turned still further and the lever 172 rides over the highest point of the cam, thereby still further depressing the link 174, whereby the pawl 177 is caused to turn ratchet wheel 163, but not a sufficient distance to bring the pawl 170 into operative relation with the first tooth of the ratchet wheel.

115 During the knitting of the foot and toe the parts described remain in inoperative position, but on the shift from oscillation to rotation at the beginning of circular knitting, the cam wheel 171 again acts upon the lever 172 and link 174 as before described, and at this time the ratchet wheel 163 is advanced a sufficient distance to bring the pawl 170 into operative relation with the ratchet wheel 163, whereupon the operation 120 of the latter proceeds as before described until the machine is stopped.

125 After the machine is stopped, the yarn is broken by hand and the stocking is pressed off the needles by turning the ma- 130

chine about two revolutions. It is then necessary to move down the half ring m to move the rear bank of needles out of action preparatory to leveling all the needles for the transferring operation. I have provided the following means for then moving down the half-ring m .

On the shaft 162 of the ratchet wheel 163 is a cam 180 (see Figs. 2 and 6). On the lever 94 is a lug 181 carrying an adjusting screw in line of travel of the cam 180. After the stocking is pressed off the needles as before stated, the machine is turned by hand until the ratchet wheel 163 is advanced 15 into such position that the cam 180 will underride the screw on lug 181, thereby lifting the corresponding end of the lever against the action of spring 99, pulling down the other end of the lever and thereby, 20 through rod 93 and bar 92, pulling down the half-ring m and moving the rear bank of needles out of operative relation with the cams on the cylinder i . The machine is then given a partial turn to bring the cams 25 of the cam cylinder opposite the needles that have thus been moved out of action, thereby leveling all the needles, as before mentioned. The transferring operation then proceeds, this operation, however, having 30 nothing to do with my present invention. After the transferring operation, the machine is again turned to bring the cams into operative relation with certain needles of the front bank. Immediately thereafter the 35 cam 180 passes beyond the screw of lug 181 and the spring 99 acts to pull down the stud 95 and the forked end of lever 94, thereby again raising the half-ring m , thus restoring 40 the rear bank of needles to operative position. At this time the lug 176 has advanced to a position just behind the hooked end of the lever 175. Consequently, there is no danger, due to the action of the spring 45 99, of the cam 180, shaft 162 and ratchet 163, being kicked forward. Further turning of the shaft 162 causes the cam 180 to engage an arm 184 on a shaft 185. This shaft carries another arm 186 (see Fig. 3), which extends between two collars 187, on a 50 rod 188, the latter being attached to one arm of the three armed lever 121. The rocking of the shaft 185 by means of the cam 180 causes the arm 186 to strike the lower collar on the rod 188, thereby swinging the lever 55 121 against the screw 118, pushing forward the rod 115, turning the gear 112 and screws 119 and thereby lifting the needle cylinder to its maximum height. The needle cylinder remains in its elevated position during 60 the knitting of only one course, as the cam 180 immediately recedes from the arm 182. Thus a single loose course is knit at the top of the leg.

During the knitting of ladies' stockings, 65 if it is not desired to form a loose course at

the top of the leg, the ratchet wheel 163 and its appurtenant mechanism is rendered inactive by any convenient means, as, for example, by disconnecting the link 168 from the gear 167. If, however, it is desired to 70 knit a loose course at the top of the leg of a ladies' stocking, the screw of the lug 181 is removed, rendering the cam 180 inoperative to actuate the lever 94.

In Figs. 3 and 6 I have shown a winder 75 and special means for operating it. The take up roller 200 of the winder turns in bearings in a supporting bracket 201. As the knit fabric passes from the machine, it passes under the take-up roller 200, thence 80 up between the latter and a presser roller 203 and thence around the latter and down to the receptacle for the stockings. The roller 203 is supported from a link 204 carried by the arm 205 extending up from the 85 bracket 201. Fast to the shaft of roller 200 is a ratchet 206. Loose on the shaft of roller 200 is a half disk 207 carrying a pawl 208 engaging the ratchet 206. On this half disk 207 is a crank pin from which extends 90 a rod 209 having a toothed end, the rod 209 resting, between its ends, on a fulcrum 210. On the constantly oscillating shaft 95 69 is a kicker arm 211 having a toothed end. A weighted chain 212 is attached to the half disk 207.

As the knitted fabric passes from the needles, it is fed forward, by the weight, through the medium of the half-disk 207, the pawl 208 and ratchet 206, and the roller 100 200. This causes the free end of rod 209 to be gradually elevated until it is brought into line with the kicker-arm 211. The latter, in its forward movement of reciprocation, then engages the rod 209 and restores the half-disk 207 to its original position (the pawl 208 slipping back upon the teeth of the ratchet 206), thus lifting the weight 105 to its upper position. The weight again starts its descent and continues to 110 descend until it is again lifted by the kicker-arm 211.

The following mechanism is provided to stop the machine in case of breakage of a thread. It will be observed, by reference 115 to Fig. 6, that the stocking on its way from the needles to the winder, engages a weighted frame 213 pivoted near its lower end on the bracket 201. The lower end of the frame 213 has a pin and slot connection 120 with one end of a link 214, the other end of the link being attached to an arm 215 on the lever 52, which, as before described, controls the belt shifting mechanism. If a thread breaks, the fabric will shortly thereafter run off the needles and the fabric will drop, thus allowing the weighted frame 213 125 to drop and, through link 214, lifting lever 52 and unlocking the belt-shifting mechanism. If, however, the belt-shifting mecha- 130

nism is actuated from any of the other hereinbefore described control devices, the pin and slot connection between the frame 213 and link 214 permits the belt-shifting mechanism to actuate without dropping the frame 213.

While in the foregoing description I have spoken of the cam cylinder as rotatable and of the needle cylinder as vertically adjustable, in accordance with the embodiment of the invention shown in the drawings, I do not intend to restrict the application of my invention to this particular type of machine to the exclusion of any well known equivalent arrangement, as that in which the needle cylinder is rotatable, and the cam cylinder vertically adjustable.

While the machine hereinbefore described embodies many novel features, it also embodies certain features embodied in earlier patents issued to me, of which the principal one is Patent No. 774,473, dated November 8, 1904.

While, in order that the construction and operation of the machine may be fully understood, I have herein described and illustrated the automatic means for stopping the machine in the event of any obstruction in the knitting mechanism tending to stop the rotation of the cam cylinder, the take-up mechanism, the mechanism for adjusting the relative vertical positions of the cylinders to lengthen or shorten the stitches and the automatic means rendered operative in the manufacture of half hose for stopping the machine and moving the rear bank of needles out of operative relation with the cam cylinder preparatory to the knitting operation, I do not herein claim these features, as the same form the subject matter of divisional applications.

Having now fully described my invention, what I claim and desire to protect by Letters Patent is:

1. In a circular knitting machine, the combination with the cam cylinder and sinker head, a driving external gear in driving engagement with the cam cylinder, a driving internal gear, means for driving said driving gears in unison, a gear in driving engagement with the sinker head, and a pinion on the shaft of the last-named gear, in driving engagement with the driving internal gear.

2. In a circular knitting machine, the combination with the cam cylinder and sinker head and gears carried respectively thereby, of a ring, a driving shaft connected with the ring, an external gear on the ring in driving engagement with the cam cylinder gear, a pinion, an internal gear on the ring in driving engagement with the pinion, and a gear on the pinion shaft in driving engagement with the sinker head gear.

3. In a circular knitting machine, the

combination with the cam cylinder and sinker head and gears carried respectively thereby, of a driving gear in driving engagement with the cam cylinder gear, a driving internal gear, a driven gear in driving engagement with the sinker head gear, a pinion on the shaft of said driven gear, in driving engagement with the driving internal gear, means for driving said driving gears in unison, the ratios of the intermeshing gears being so proportioned as to impart equal angular speeds of rotation to the two first-named gears, whereby the cam cylinder and sinker head will revolve as if secured together while the latter will be driven by an indirect drive and the momentum of the driving parts substantially reduced.

4. In a circular knitting machine, the combination with the cam cylinder and sinker head, of a driving external gear in driving engagement with the cam cylinder, a driving internal gear, a gear in driving engagement with the sinker head, and a pinion on the shaft of the last-named gear, in driving engagement with the driving internal gear, a driving shaft, and a yielding driving connection between the shaft and both driving gears adapted to be rendered inoperative upon predetermined resistance to rotation of said driving gears.

5. In a circular knitting machine, the combination with a rotatable cylinder and a gear carried thereby, of a casing, a ring whose lower part rotates in the casing, an external gear on the part of the ring projecting above the casing, in driving engagement with the cam cylinder gear, a driving shaft extending through the wall of the casing, and a yielding driving connection within the casing and between the shaft and the ring adapted to be rendered inoperative upon predetermined resistance to rotation of the cylinder.

6. In a circular knitting machine, the combination with a rotatable cylinder, of a clutch shaft and driving connections therefrom to the cylinder, clutch pinions adapted to alternately engage the clutch shaft, means to rotate one pinion and oscillate the other pinion, two cams each having high and low parts corresponding respectively in length to the low and high parts of the other, a lever, two arms thereon engaging the respective cams and adapted to be actuated thereby to move the lever in one direction or the other, means actuated by the lever to clutch one or the other pinion to the shaft (dependent upon the direction in which the lever is moved) and unclutch the remaining pinion, means to turn said cams, pattern mechanism, and means controlled by the pattern mechanism to control the operation of the cam-actuating means.

7. In a circular knitting machine, the

- combination with a rotatable cylinder, of an upright shaft, driving connections between the shaft and cylinder, a clutch on the shaft, clutch pinions respectively above and below the clutch, a post, arms on the post carrying said pinions respectively, means to rotate one pinion and oscillate the other pinion, a lever carrying the post, two arms thereon, two rotatable cams each having high and low parts corresponding respectively in length to the low and high parts of the other, said cams engaging the respective lever arms, means to turn the cams, pattern mechanism, and means controlled by the pattern mechanism to control the operation of the cam-actuating means. 5
8. In a circular knitting machine, the combination with a rotatable cylinder, of driving connections thereto, means to actuate said driving connections to impart a rotary motion to the cylinder, means to actuate said driving connections to impart an oscillatory motion to the cylinder, a lever adapted in different positions to connect said driving connections with the two actuating means respectively, two arms on the lever, two rotatable cams each having high and low parts corresponding respectively in length to the low and high parts of the other, said cams 10 engaging the respective lever arms, means to turn the cams, pattern mechanism, and means controlled by the pattern mechanism to control the operation of the cam actuating means.
9. In a circular knitting machine, the combination with a rotatable cylinder, of driving connections thereto, means to actuate said driving connections to impart a rotary motion to the cylinder, means to actuate the driving connections to impart an oscillatory motion to the cylinder, a shaft, a ratchet thereon having a number of relatively short teeth of substantially equal length and one relatively long tooth, a pawl for actuating the ratchet, means to reciprocate the pawl, pattern mechanism, means controlled by the pattern mechanism to turn the ratchet to move the long tooth thereof into position to enable the pawl to turn the ratchet, fashioning rack plates, means controlled by the ratchet to connect said driving connections with one of the actuating means therefore and disconnect them from the other actuating means and render said rack plates operative, and means controlled by the rack plates to cause said pawl to be lifted into and out of operative engagement with one of the short teeth of the ratchet. 15
10. In a circular knitting machine, the combination with a rotatable cylinder and the needles, of driving connections to the cylinder, means to actuate said driving connections to impart an oscillatory motion to the cylinder, means to actuate said driving connections to impart a rotary motion to the 20 cylinder, an annular camway turning with said actuating means at such a speed that it makes one complete rotation at each complete oscillation back and forth of the cylinder when the latter is being oscillated, fashioning rack plates for moving certain needles consecutively into and out of operative position during oscillation of the cylinder, a cam roller, connections between the cam roller and the fashionable rack plates, shifting means to connect said driving connections with one actuating means and disconnect them from the other and vice versa, connections between said shifting means and the cam roller whereby the latter is moved into the cam way at the beginning of the oscillatory movement of the cylinder and out of the cam way at the conclusion of said oscillatory movement, pattern mechanism, and means controlled by the pattern mechanism to control the operation of the shifting means. 25
11. In a circular knitting machine, the combination with a rotatable cylinder, the needles, and fashioning rack plates for moving certain of said needles consecutively into and out of operative position, of an upright shaft, driving connections between the shaft and cylinder, a clutch on the shaft, clutch pinions respectively above and below the clutch, vertically movable shifting means carrying said pinions, means to oscillate one pinion and rotate the other including a gear wheel having a cam way, a cam roller, connections between the cam roller and the 30 fashioning rack plates, connections between the cam roller and the shifting means, pattern mechanism, and means controlled by the pattern mechanism to control the operation of the shifting means. 35
12. In a circular knitting machine, the combination with a rotatable cylinder, the needles, and fashioning rack plates for moving certain of said needles consecutively into and out of operative position, of an upright shaft, driving connections between the shaft and cylinder, a clutch on the shaft, clutch pinions respectively above and below the clutch, a post, arms on the post carrying the pinions respectively, means to oscillate one pinion and rotate the other including a gear wheel having a cam way, a cam roller, connections between the cam roller and the 40 fashioning rack plates, connections between the cam roller and one of said arms, pattern mechanism, and means controlled by the pattern mechanism to move the post vertically. 45
13. In a circular knitting machine, the combination with a rotatable cylinder, and the needles, of an upright shaft, driving connections from the shaft to the cylinder, a clutch on the shaft, a rotary pinion and an oscillatory pinion loose on the shaft, one above and the other below the clutch and each having members adapted to engage the 50

- clutch, a post, arms carried by the post and supporting both pinions whereby when the post is moved vertically one pinion will be engaged with the clutch and the other pinion disengaged therefrom, means to render simultaneously inoperative about half the needles, connections between the post and the last named means, fashioning rack plates adapted to consecutively move out of and into action certain of the remaining needles, means to drive said pinions, means to actuate the fashioning rack plates, and means connected with and adapted to be actuated by the post and arms to move the fashioning rack plate actuating means into operative relation with the pinion-driving means.
14. In a circular knitting machine, the combination with the needle cylinder and cam cylinder, of a support, a plurality of pinions interposed between the support and one of the cylinders and having threaded shafts engaging one of the last named members, a rotatable gear engaging all the pinions, whereby when the gear is turned the last named cylinder is raised or lowered, a device connected with and adapted to actuate the gear, pattern mechanism, means controlled by the pattern mechanism having a definite limit of movement and adapted to engage and operate the gear-actuating device, the latter being adjustable to vary the extent to which it is moved by its operating means, thereby enabling the degree of vertical movement of the vertically movable cylinder to be governed.
15. In a circular knitting machine, the combination with the needle cylinder and cam cylinder, of a support, a plurality of pinions interposed between the support and one of the cylinders and having threaded shafts engaging one of the last named members, a rotatable gear engaging all the pinions, whereby when the gear is turned the last named cylinder is raised or lowered, mechanism connected with and adapted to actuate the gear, a reciprocable lever adapted to actuate said mechanism, pattern mechanism, and means controlled by the pattern mechanism to operate the reciprocable lever.
16. In a circular knitting machine, the combination with the needle cylinder, and cam cylinder, of a support, a plurality of pinions interposed between the support and one of the cylinders and having threaded shafts engaging one of the last named members, a rotatable gear engaging all the pinions, whereby when the gear is turned the last named cylinder is raised or lowered, a rod connected with the gear, an adjustable abutment on the rod, a reciprocable lever adapted to engage said abutment and thereby actuate said rod and gear, pattern mechanism, and means controlled by the pattern mechanism to operate the reciprocable lever.
17. In a circular knitting machine, the combination with the needle cylinder and cam cylinder, of devices engaging one of the cylinders at different points for adjusting it vertically, mechanism for simultaneously operating all of said devices, a plurality of abutments carried by said mechanism, a plurality of levers adapted to respectively engage said abutments, pattern mechanism, and means controlled by the pattern mechanism to actuate said levers successively whereby the vertically adjustable cylinder may be raised to successively different heights.
18. In a circular knitting machine, the combination with the needle cylinder and cam cylinder, of mechanism for vertically moving one of the cylinders, said mechanism including a rod, an abutment thereon, a lever adapted when operated to engage said abutment and move the rod a definite distance, a second abutment on the rod, a second lever adapted when operated to engage the second abutment and move the rod a further distance; pattern mechanism, and means controlled by the pattern mechanism to operate said levers respectively whereby the vertically movable cylinder will be raised first to an intermediate height and then to a greater height.
19. In a circular knitting machine, the combination with a cam cylinder and a needle cylinder, of two ratchet wheels, driving connections to one of the cylinders, means to actuate the driving connections to impart a rotary motion to the cylinder, means to actuate the driving connections to impart an oscillatory motion to the cylinder, means actuated by the first ratchet wheel to connect said driving connections with one of said actuating means and disconnect them from the other, mechanism to lift the other of said cylinders, connections from the first ratchet wheel to and adapted to operate the cylinder-lifting mechanism, connections from the second ratchet wheel to and adapted to operate the cylinder-lifting mechanism, a pattern chain, and connections from the pattern chain controlling the operation of both ratchet wheels.
20. In a circular knitting machine, the combination with a cam cylinder and a needle cylinder, of two ratchet wheels, driving connections to one of the cylinders, means to actuate the driving connections to impart a rotary motion to the cylinder, means to actuate the driving connections to impart an oscillatory motion to the cylinder, means actuated by the first ratchet wheel to connect said driving connections with one of said actuating means and disconnect them from the other, mechanism to lift the other of said cylinders, connections from the first ratchet wheel to and adapted to operate the cylinder-lifting mechanism, connections from the second ratchet wheel to and adapt-

- ed to operate the cylinder-lifting mechanism, connections from the first ratchet wheel to and adapted to operate the second ratchet wheel, a pattern chain, and connections from the pattern chain controlling the operation of both ratchet wheels. 5
21. In a circular knitting machine, the combination with a cam cylinder and a needle cylinder and driving connections to one of the two cylinders, of rotary mechanism and oscillatory mechanism and driving means therefor, two cams, means operated by the cams to connect said driving connections with the rotary mechanism and oscillatory mechanism respectively, two additional cams, mechanism to lift the other of said cylinders, connections from the two cams to and adapted to actuate said cylinder lifting mechanism to lift the cylinder to respectively different heights, a ratchet wheel, connections between the ratchet wheel and the four cams whereby they all rotate together, a pattern chain, mechanism controlled thereby controlling the turning of the ratchet, and means controlled by the pattern chain to render alternately operative and inoperative the connections between one of the cams and the cylinder lifting mechanism. 10
22. In a circular knitting machine, the combination with a cam cylinder and a needle cylinder and driving connections to one of the two cylinders, of rotary mechanism and oscillatory mechanism and driving means therefor, a ratchet wheel having a relatively long tooth and a number of shorter teeth, a pawl adapted to operate the ratchet wheel, means to operate the pawl, means actuated by the ratchet wheel to connect said driving connections with said rotary mechanism and disconnect it from the oscillatory mechanism and vice versa, fashioning rack plates adapted to move certain of the needles consecutively out of and into operative relation with the cam cylinder, means actuated by the ratchet wheel to operatively connect the fashioning rack plates with said driving means, two sets of mechanisms, both operatively connected with said ratchet wheel to lift the vertically movable cylinder, pattern mechanism, means controlled by the pattern mechanism to turn the ratchet wheel to bring the long tooth thereof into position to enable the pawl to operate the ratchet and thereby cause the latter to change the movement of the rotatable cylinder from rotation to oscillation, cause the fashioning rack plates to operate, and operate the first cylinder-lifting mechanism, means controlled by the fashioning rack plates to render the pawl inoperative during their operation, whereby at the conclusion of the operation of the fashioning rack plates the pawl will again operate the ratchet wheel to change the movement of the 15
- rotatable cylinder from oscillation to rotation and actuate the second cylinder-lifting mechanism, and means operated by the pattern mechanism to render the second cylinder lifting mechanism alternately operative and inoperative. 20
23. In a circular knitting machine, the combination with a cam cylinder and a needle cylinder and driving connections to one of the two cylinders, of rotary mechanism and oscillatory mechanism and driving means therefor, a shaft, shifting means connected with and operated by the shaft to connect said driving connections with the rotary mechanism and disconnect it with the oscillatory mechanism and vice versa a top motion control-rod, means connected with and operated by said shaft to operate said control-rod, a pattern chain, means controlled by the pattern chain controlling the turning of said shaft, mechanism for lifting one of the cylinders, mechanism to lock said control-rod in the position to which it has been moved by said shaft, two rotary cams, one of said cams adapted to operate the cylinder-lifting mechanism and the other the control-rod-locking mechanism, and means controlled by the pattern chain to turn said cams in unison. 25
24. In a circular knitting machine, the combination with a cam cylinder and a needle cylinder and driving connections to one of the two cylinders, of rotary mechanism and oscillatory mechanism and driving means therefor, a shaft, shifting means connected with and operated by said shaft adapted to connect said driving connection successively with said oscillatory mechanism and with said rotary mechanism, a top-motion control-rod, means actuated by the shaft in the shift to oscillation to lift said rod and in the shift to rotation to allow the rod to drop, a pattern chain, means controlled by the pattern chain controlling the turning of said shaft, mechanism for lifting one of the cylinders, mechanism to hold said rod lifted in certain shifts to rotation, two rotary cams one of said cams adapted to operate the cylinder-lifting mechanism and the other the rod-holding mechanism, and means controlled by the pattern chain to turn the cams in unison. 30
25. In a circular knitting machine, the combination with a cam cylinder and a needle cylinder, of mechanism to lift one of said cylinders, an intermittently driven shaft, a cam adapted to actuate the cylinder lifting mechanism, a ratchet turning with the cam and having a toothed portion and an untoothed portion, a pawl adapted to actuate the ratchet, operative connections between said shaft and the pawl whereby the latter is intermittently operated, a pattern chain, means controlled by the pattern chain controlling the turning of said shaft, and 35

- means enabling the pattern chain to turn the ratchet to bring the pawl into operative relation therewith, whereby the pattern chain determines whether the cylinder lifting mechanism shall be operated by said pawl. 5
26. In a circular knitting machine, the combination with a cam cylinder and a needle cylinder, of mechanism to lift one of said cylinders, an intermittently driven shaft, a cam adapted to actuate the cylinder lifting mechanism, a ratchet turning with the cam and having a toothed portion and an untooothed portion, a pawl adapted to actuate the ratchet, operative connections between said shaft and the pawl whereby the latter is intermittently operated, a pattern chain, means controlled by the pattern chain controlling the turning of said shaft, means enabling the pattern chain to turn the ratchet to bring the pawl into operative relation therewith, and means operated by the pattern chain to directly operate said pawl. 10 15 20 25
27. In a circular knitting machine, the combination with a cam cylinder and a needle cylinder, of mechanism to lift one of said cylinders, an intermittently driven shaft, a cam adapted to actuate the cylinder lifting mechanism, means actuated from said shaft to turn the cam, a pattern chain, means actuated by the pattern chain controlling the operation of said shaft, and means actuated by the pattern chain to turn the cam beyond the position to which it has been turned by said shaft. 30 35
28. In a circular knitting machine, the combination with a vertically movable cylinder, of mechanism to lift the cylinder, levers adapted to actuate said mechanism, an intermittently driven shaft, two cams turning with the shaft one of which is adapted to actuate one lever, means actuated by the second cam to operate the second lever, the driving shaft, means actuated from the driving shaft to turn the driven shaft when the latter is turned to a certain position, pattern mechanism, and means actuated by the pattern mechanism to turn the driven shaft to bring it into operative relation with its actuating means. 40 45 50
29. In a circular knitting machine, the combination with a vertically movable cylinder, of mechanism to lift the cylinder, a lever adapted to actuate said mechanism, a shaft, a cam turning with the shaft adapted to actuate the lever, the driving shaft, means actuated from the driving shaft to turn the first shaft when the latter is turned to a certain position, the pattern chain, a second lever, a lug on the chain adapted to operate the second lever, a pawl adapted to turn the first shaft to bring it into operative relation with its actuating means, and connections between the second lever and the pawl. 55 60 65
30. In a circular knitting machine, the combination with a vertically movable cylinder, of mechanism to lift the cylinder, a cam adapted to operate said mechanism, a ratchet turning with the cam and having an untooothed portion, a pawl adapted to actuate the ratchet, a shaft, a cam turning with the shaft, a lever operated by the cam, a connection between the lever and the pawl, the driving shaft, means actuated from the driving shaft to turn the first shaft when the latter is turned to a certain position, a pattern chain, means actuated by the pattern chain to turn the first shaft to bring it into operative relation with its driving means, and means actuated by the pattern chain to turn the ratchet to bring its toothed portion in operative relation with said pawl. 70 75 80 85
31. In a circular knitting machine, the combination with a vertically movable cylinder, of mechanism to lift the cylinder, a cam adapted to operate said mechanism, a ratchet turning with the cam and having an untooothed portion, a pawl adapted to actuate the ratchet, a shaft, a cam turning with the shaft, a lever operated by the cam, a connection between the lever and the pawl, the driving shaft, means actuated from the driving shaft to turn the first shaft when the latter is turned to a certain position, a pattern chain, means actuated by the pattern chain to turn the first shaft to bring it into operative relation with its driving means, and means actuated by the pattern chain to turn the ratchet to bring its toothed portion in operative relation with said pawl, a lever connected with the pawl and a lug on the chain adapted to actuate the last named lever and thereby cause the ratchet to turn independently of its driving connections with the first shaft. 90 95 100 105
32. In a circular knitting machine, the combination with a vertically movable cylinder, of two sets of mechanism to lift the cylinder, a shaft, a cam turning with the shaft adapted to actuate the first cylinder-lifting mechanism, a second cam turning with the shaft, a third cam adapted to actuate the second cylinder-lifting mechanism, a ratchet turning with the third cam having an untooothed portion, a pawl adapted to actuate the ratchet, a lever operated by the second cam, a connection between the lever and the pawl, a pattern chain and means actuated by the pattern chain to turn the ratchet into operative relation with the pawl. 110 115 120
33. In a circular knitting machine, the combination with a vertically movable cylinder, of two sets of mechanism to lift the cylinder, a shaft, a cam turning with the shaft adapted to actuate the first cylinder-lifting mechanism, a second cam turning with the shaft, a third cam adapted to actuate the second cylinder-lifting mechanism, a ratchet turning with the third cam hav- 125 130

ing an untoothed portion, a pawl adapted to actuate the ratchet, a lever operated by the second cam, a connection between the lever and the pawl, the pattern chain, means operated by the pattern chain and controlling the operation of the shaft, a second lever connected with the pawl and adapted to actuate it independently of the second cam, means actuated by the pattern chain to bring the ratchet into operative relation with the pawl, and a lug on the chain adapted to operate the second lever.

34. In a circular knitting machine, the combination with the needle cylinder and the cam cylinder, of two shafts geared together, a main pattern ratchet wheel on one of the shafts, oscillatory mechanism and rotary mechanism, driving connections to one of the cylinders, two cams on one of the shafts, means adapted to be operated by said cams to connect the driving connections with the oscillatory mechanism and rotary mechanism respectively, mechanism to move one of the cylinders vertically, a cam on one of the shafts adapted to operate the cylinder lifting mechanism, and means to turn the pattern ratchet.

35. In a circular knitting machine, the combination with the needle cylinder and the cam cylinder, of two shafts geared together, a main pattern ratchet wheel on one of the shafts, a pawl adapted to actuate said ratchet wheel when the shafts are turned to a certain position, means to actuate the pawl, oscillatory mechanism and rotary mechanism, driving connections to one of the cylinders, means actuated by one of the shafts to connect the driving connections with the rotary mechanism and oscillatory mechanism respectively, mechanism to move one of the cylinders vertically, means actuated by the shafts to operate the cylinder lifting mechanism, a pattern chain, and means actuated by the pattern chain to turn the shafts into position to enable the ratchet wheel to be actuated by the pawl.

36. In a circular knitting machine, the combination with the needle cylinder and the cam cylinder, of two shafts geared together, a main pattern ratchet wheel on one of the shafts, a pawl adapted to actuate said ratchet wheel when the shafts are turned to a certain position, means to actuate the pawl, oscillatory mechanism and rotary mechanism, driving connections to one of the cylinders, two cams on one of the shafts, means adapted to be operated by said cams to connect the oscillatory mechanism and rotary mechanism respectively with said driving connections, two other cams on one of the shafts, two sets of mechanism actuated respectively by the last two cams to move one of the cylinders vertically, a pattern chain, means actuated by the pattern chain to turn the shafts into position to enable the ratchet

wheel to be actuated by the pawl, and means actuated by the pattern chain to render inoperative one set of mechanism for operating the vertically movable cylinder.

37. In a circular knitting machine, the combination with the needle cylinder and the cam cylinder, of two shafts geared together, a main pattern ratchet wheel on one of the shafts, a pawl adapted to actuate said ratchet wheel when the shafts are turned to a certain position, means to actuate the pawl, oscillatory mechanism and rotary mechanism, driving connections to one of the cylinders, two cams on one of the shafts, means adapted to be operated by said cams to connect the oscillatory mechanism and rotary mechanism respectively with said driving connections, two other cams on one of the shafts, two sets of mechanism actuated respectively by the last two cams to move one of the cylinders vertically, a top motion control-rod, a cam on one of the shafts adapted to actuate said rod, a pattern chain, means actuated by the pattern chain to turn the shafts into position to enable the ratchet wheel to be actuated by the pawl, and means actuated by the pattern chain to render inoperative one set of mechanism for operating the vertically movable cylinder.

38. In a circular knitting machine, the combination with the cam cylinder and needle cylinder, of driving connections to one of the cylinders, a control shaft, rotary mechanism and oscillatory mechanism, shifting means actuated by the control shaft to connect the driving connections alternately with the rotary mechanism and oscillatory mechanism, a ratchet having a number of teeth, a pawl adapted to actuate the ratchet when the latter is turned into a certain position, a driving shaft, means actuated thereby to operate the rotary and oscillatory mechanism, the control shaft and the pawl, means actuated by the control shaft to turn the ratchet into operative relation with the pawl, mechanism to stop the rotation of the driving shaft, and means controlled by the ratchet wheel to operate the stop mechanism, whereby the ratchet may be brought into operative relation with the pawl after a given shift from oscillation to rotation, and the machine stopped after the ratchet wheel has been turned a predetermined distance by the pawl and therefore after a predetermined number of courses of circular knitting.

39. In a circular knitting machine, the combination with the cylinder and needle cylinder, of rotary mechanism and oscillatory mechanism, driving connections to one of the cylinders, a control shaft, means actuated by the control shaft adapted at each rotation thereof to connect said driving connections successively with the oscillatory mechanism and rotary mechanism, a ratchet

having a number of teeth and an untoothed portion, a pawl adapted to actuate the ratchet, a driving shaft, connections therefrom to the pawl, the rotary and oscillatory mechanism and the control shaft, a cam turning with the control shaft; a second pawl to turn the ratchet, means actuated by the control shaft to operate the second pawl and thereby turn the ratchet a limited distance at each rotation of the control shaft, whereby the ratchet may be brought into operative relation with the first pawl after a given shift from oscillation to rotation, mechanism to stop the rotation of the driving shaft, and means operated by the ratchet to control the operation of the stop mechanism.

40. In a circular knitting machine, the combination with the cam cylinder and needle cylinder, of driving connections to one of the cylinders, rotary mechanism and oscillatory mechanism, a control shaft, shifting means actuated by the control shaft to connect the driving connections alternately with the rotary mechanism and oscillatory mechanism, an arm carried by the shifting means, a stud movable in said arm, a lever connected with the stud, a spring between the stud and the arm, means connected with

and operated by the lever to move certain needles out of operative relation with the cam cylinder, and independent means to operate the lever, whereby the last named means may be operated either from the control shaft or independently thereof.

35

41. In a circular knitting machine, the combination with the cam cylinder and needle cylinder, of mechanism for moving one of said cylinders vertically, a control shaft, the driving shaft, means actuated by the driving shaft to drive the control shaft, pattern mechanism, means controlled by the pattern mechanism to control the operation of the control shaft, two cams turning with the control shaft, separate means, actuated by the respective cams, to operate said cylinder-lifting mechanism, and means actuated by the driving shaft and independent of said control shaft and cams, to operate one of said cylinder-lifting mechanisms.

45

In testimony of which invention, I have hereunto set my hand, at Philadelphia, on this 16th day of May, 1912.

HARRY A. HOUSEMAN.
